W. J. CARLEY,
WIRE CLAMP,
APPLICATION FILED JAN. 31, 1920.

1,382,620.

Patented June 28, 1921.

Inventor

W. J. Carley

By Watson E. Coleman
Attorney

REISSUED
AS NO. 16704
AUG 16 1921

UNITED STATES PATENT OFFICE.

WILLIAM JAMES CARLEY, OF CULPEPER, VIRGINIA, ASSIGNOR TO MARIE BESSIERS,
OF CULPEPER, VIRGINIA.

WIRE-CLAMP.

1,382,620.

Specification of Letters Patent. Patented June 28, 1921.

Application filed January 31, 1920. Serial No. 255,384.

To all whom it may concern:

Be it known that I, WILLIAM JAMES CARLEY a citizen of the United States, residing at Culpeper, in the county of Culpeper and State of Virginia, have invented certain new and useful Improvements in Wire-Clamps, of which the following is a specification, reference being had to the accompanying drawings.

10 This invention relates to certain improvements in wire clamps and has relation more particularly to a device of this general character especially designed and adapted for use in connection with a trolley wire, and it is an object of the invention to provide a novel and improved clamp of this general character whereby the wire may be effectively supported from a hanger or the like.

Another object of the invention is to provide a novel and improved device of this general character embodying a pair of coacting clamping jaw members or ears together with novel and improved means whereby said clamping jaw members or ears are prevented from falling out.

An additional object of the invention is to provide a device of this general character having novel and improved means whereby the clamping jaw members or ears are caused to tightly engage the wire with which the same is employed.

The invention consists in the details of construction and in the combination and arrangement of the several parts of my improved clamp whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:

Figure 1 is a view in elevation of a wire clamp constructed in accordance with an embodiment of my invention;

Fig. 2 is a sectional view taken substantially on the line 2-2 of Fig. 1;

Fig. 3 is a view in top plan of the structure as herein disclosed with the hanger stud engaging member removed; and

Fig. 4 is a view in plan of the split ring as herein employed.

55

As disclosed in the accompanying drawings, 1 denotes a suspension member or nut provided at one end portion and at substantially the axial center thereof with the socket 2, or the like, adapted to receive a stud or hanger of a conventional type. The nut 1 includes a shank portion 3 provided adjacent its outer or free end with an annular groove or channel 4. Inwardly of said groove or channel 4, the shank 3 is provided with the peripheral threads 5.

The jaw members or ears 6 are of duplicate construction and are adapted to be tightly clamped or engaged with the wire W. Each of the jaw members 6 is provided with an inwardly disposed lip or flange 7 substantially semicircular in form and which engages within the groove 4. Each of the members 7 is also provided with a ledge 8 and an upstanding flange 9, said lip and flange also being substantially semicircular.

10 denotes a nut engaged with the threaded portion 5 which when screwed down upon the ledges 8 of the jaw members 6 causes said jaw members to tightly clamp the wire W. 80 The end portion of the bore of the nut 10 opposed to the member 6 is enlarged to receive the flanges 9 whereby the jaws 6 are prevented from falling out.

I also find it of advantage to provide the shank 3 above the threaded portion 5 with a second annular groove or channel 11 in which is adapted to be tightly pinched or otherwise fitted a split ring 12, of soft iron, and which ring 12, when applied, extends 90 beyond the periphery of the shank 3 and serves to prevent the nut 10 from screwing up too far with respect to the jaw members 6 whereby further means are provided to prevent said jaw members from falling or dropping out. The annular groove or channel 4 in the shank 3 permits the jaw members or ears 6 to swivel or rotate around the shank 3 so that said jaw members or ears may be effectively engaged with the wire W. 100

As is clearly illustrated in Fig. 2, the wall of the socket 2 of the suspension member 1 is threaded so that the same may be effectively engaged with a stud or hanger of the type now generally employed. It is also to be particularly noted that the outer or

upper end of the member 1 is provided with an outstanding hexagonal head or the like to afford means whereby said member 1 may be conveniently screwed or threaded upon 5 the hanger or stud.

From the foregoing description, it is thought to be obvious that a clamp constructed in accordance with my invention is particularly well adapted for use by reason 10 of the convenience and facility with which it may be assembled and operated, and it will also be obvious that my invention is susceptible of some change and modification without departing from the principles and 15 spirit thereof, and for this reason, I do not wish to be understood as limiting myself to the precise arrangement and formation of the several parts herein shown in carrying out my invention in practice except as 20 hereinafter claimed.

I claim:-

1. A clamp for a trolley wire comprising, in combination, a member adapted for engagement with a hanger stud, two clamping 25 members engaged with the member and capable of rotation therearound, each of said clamping members being provided with an external ledge, and a tubular member threaded upon the first named member and 30 adapted to engage the ledges of the clamping members to force the clamping members one toward the other, the faces of the second named members opposed to the clamping members each being provided with a recess, 35 said clamping members being provided with upstanding flanges extending within said recesses, the recess of said second member constituting an enlargement of the bore of said second member.

2. A clamp for a trolley wire comprising, in combination, a member adapted for engagement with a hanger stud, an end portion 40 of the member being provided with an annular channel, clamping members provided 45 with inwardly directed ears seating within the channel of said first named member.

ber, each of said clamping members being provided with an external ledge, and a member threaded upon the first named member and engageable with the ledges of the clamping members to force said clamping members one toward the other.

3. A clamp for a trolley wire comprising, in combination, a member adapted for engagement with a hanger stud, an end portion 50 of the member being provided with an annular channel, clamping members provided with inwardly directed ears seating within the channel of said first named member, each of said clamping members being provided with an external ledge, a member threaded upon the first named member and engageable with the ledges of the clamping members to force said clamping members one 55 toward the other, and means carried by the first named member to limit the movement of the last named member in a direction away from the ledge.

4. A clamp for a trolley wire comprising, in combination, a member adapted for engagement with a hanger stud, an end portion 70 of the member being provided with an annular channel, clamping members provided with inwardly directed ears seating within the channel of said first named member, each 75 of said clamping members being provided with an external ledge, a member threaded upon the first named member and engageable with the ledges of the clamping members to force said clamping members one toward 80 the other, and means carried by the first named member to limit the movement of the last named member in a direction away from the ledge, said second named member being provided with an annular recess, the 85 clamping members being provided with flanges extending within said recess, said flanges being arranged within the recess at all times.

In testimony whereof I hereunto affix my 90 signature.

WILLIAM JAMES CARLEY.
